TEETH-LOCKING COMB

Filed May 18, 1948

UNITED STATES PATENT OFFICE

2,533,067

TEETH-LOCKING COMB

Jack Taren and Aaron Leon, Los Angeles, Calif.

Application May 18, 1948, Serial No. 27,624

3 Claims. (Cl. 132—23)

1

This invention relates to combs and more particularly to teeth-locking combs.

The general object of the invention is to provide an improved comb of the character stated, constructed and arranged with fixed teeth and with spring-actuated clamping teeth, for clamping hair between said teeth for holding the hair in place, and for holding the comb in an attractive position in the hair as an ornament.

Other objects and advantages will appear hereinafter as this specification progresses.

The invention is illustrated in the annexed drawing which forms a part of this specification and in which:

Fig. 1 is a perspective of the comb with its clamping teeth held against its fixed teeth.

Fig. 2 is a perspective of the comb with its clamping teeth moved away and spaced from its fixed teeth.

Fig. 3 is a plan view of the comb partly broken away and in section showing certain features of construction.

Fig. 4 is a bottom plan view of the comb.

Fig. 5 is a perspective of the cover of the back of the comb.

Fig. 6 is a perspective of the fixed comb member of the comb.

Fig. 7 is a perspective of the slidable comb member of the comb.

Fig. 8 is a fragmentary longitudinal section of the comb taken on line 8—8 of Fig. 3, showing the slidable comb member held under spring pressure in position with its clamping teeth against the teeth of the fixed comb member.

Fig. 9 is a view like Fig. 8 except that the slidable comb member is shown pressed inwardly against spring tension with the teeth of said comb member moved away from the teeth of the fixed comb member.

Fig. 10 is a view of the pressure spring for the slidable comb member.

Referring more particularly to the drawing in which the same parts are designated by the same reference numerals in all of the figures, the comb includes generally a fixed-comb member 1, a slidable comb member 2, a spring 3 acting upon said slidable comb member to force the teeth thereof against the teeth of said fixed-comb member, and a cover 4 for the back of said fixed comb member for holding said slidable comb member in operative position in said fixed-comb member.

The fixed-comb member 1 comprises a laterally curved channel back 5, and a plurality of fixed teeth 6 depending from the lower wall 7 of said

2

back in spaced relation from one end of said back to the other, there being openings 8 in said lower wall of said back between said fixed teeth 6. One end of said channel back 5 is closed by an end wall 9, while the other end of said channel back is open as indicated at 10.

The slidable comb member 2 comprises a laterally curved solid plunger back 11 and a plurality of clamp teeth 12 depending from the lower side of said back in spaced relation from one end of said back to the other, there being a slot 13 in said back extending longitudinally from the rear end thereof, for the purpose hereinafter more fully described.

Fig. 15 The back cover 4 is in the form of an inverted channel comprising an upper wall 14, a pair of side walls 15 depending from said upper walls, and an end wall 16 closing one end of the cover, the other end 17 of said cover being open, the lower edges of said side walls 15 being formed with inturned flanges 18, respectively.

The comb is assembled as follows:

The slidable comb member 2 is positioned within the fixed comb member 1 by first placing the spring 3 in the slot 13 in the back 11 of said slidable comb member and compressing said spring inwardly from its outer end against the inner end of said slot 13, and then introducing the clamp teeth 12 of said slidable comb member 2 downwardly through the channel back 5 of the fixed-comb member 1 and through the slots 8, respectively, in the lower wall 7 of said channel back, until the back 11 of said slidable comb member 2 is within the channel back 5 of the fixed-comb member 1, with the lower side of said back 11 resting upon said lower wall 7 of said channel back 5, and with the outer end of the spring 3 engaging the end wall 9 of said channel back 5 and forcing the slidable comb member 2 forwardly, so that its clamp teeth 12 engage the adjacent fixed teeth 6 of the fixed comb member 1, and the forward end of the back 11 of the slidable comb member 2 projects forwardly beyond the open end 10 of the channel back 5 of the fixed-comb member 1, as shown in Fig. 1 of the drawing. The inverted channel cover 4 is then placed over the channel back 5 of the fixed-comb member 1 by slipping the forward open end 17 of said cover over the closed end 9 of said channel back, with the inturned flanges 18 on the lower edges of the side walls 15 of said cover extending under the lower side edges 19 of the channel back 5 of the fixed-comb member 1, until the forward open end 17 of said cover coincides with the forward open

end 10 of said channel back 5 and the rear end wall 18 of cover engages the rear end wall 9 of said channel back of the fixed comb member 1, as shown in Figs. 1 and 2 of the drawing, whereby the cover closes the upper open side of the channel back 5 of the fixed-comb member 1 and retains the slidable comb member 2 in operative position within the fixed comb member 1, and said cover further provides a neat finish for the back of the comb.

The operation of the comb is as follows:

By pressing the forward projecting end of the back 11 of the slidable comb member 2, as shown in Fig. 1, said member is pressed rearwardly in the fixed comb member 1, against the tension of the spring 3, until the clamp teeth 12 are spaced rearwardly sufficiently from the fixed teeth 6, respectively, as shown in Fig. 2. The spaced teeth 6 and 12 of the comb are then forced into the hair, which is gathered into a suitable arrangement and form, and the pressure against the forward end of the back 5 of the slidable comb member 2 is then released, whereupon the spring 3 forces the slidable comb member 2 forwardly in the fixed comb member 1, until the hair is clamped and held between the clamp teeth 12 and the fixed teeth 6 of the comb thus locking the hair in position in the arrangement and form in which it is gathered, and locking the comb in the hair in an attractive position so that the comb provides an ornament for the hair.

To unlock and remove the comb from the hair it is only necessary to press the forward end of the back 11 of the slidable comb member 2 rearwardly against the tension of the spring 3, until the clamp-teeth 12 of said slidable comb member are spaced from the fixed-teeth 6 of the fixed comb member 1, so that the teeth of the comb release the hair, whereupon the comb is withdrawn from the hair.

The cover 4 may be made of various metals, plastics and other materials and of various ornamental designs, and the cover being detachable, a number of different interchangeable covers may be used on the same comb.

We claim:

1. A comb comprising a fixed comb member formed with a channel back and fixed pointed teeth depending from said back, a slidable comb

member formed with a back slidably fitted in said channel back, and with pointed clamp teeth depending from said slidable back between said fixed teeth, a spring interposed between said fixed comb member and said slidable comb member for normally holding said slidable member in position with one side of its clamp teeth against the adjacent side of said fixed teeth of said fixed comb member and with the forward end of said slid- 10 able back projecting beyond the forward end of said channel back to be pressed to space said clamp teeth from said fixed teeth.

2. A comb as claimed in claim 1 including a cover slidably fitted over said channel back of said fixed comb member for closing the upper side of said channel back and for engaging the back of said slidable comb member for holding said slidable comb member within said comb member.

3. A comb as characterized by claim 1 includ- 20 ing an inverted channel cover slidably fitted over said channel back of said fixed comb member for closing the upper side of said channel back and for engaging the back of said slidable comb member for holding said slidable comb member within said fixed comb member, the lower edges of the side walls of said inverted channel cover being formed with inturned longitudinal flanges for extending under the lower longitudinal edges 25 of said channel back of said fixed comb member.
